DESIGN FOR A GARBAGE RECEPTACLE

Edward F. Kautz, Detroit, Mich.

Application April 7, 1945, Serial No. 118,888

Term of patent 14 years

(Cl. D58—17)

To all whom it may concern:

Be it known that I, Edward F. Kautz, a citizen of the United States, residing at Detroit, in the county of Wayne and State of Michigan, have invented a new, original, and ornamental Design for a Garbage Receptacle, of which the following is a specification, reference being had therein to the accompanying drawing, forming a part thereof.

In the drawing:

What I claim is:

The ornamental design for a garbage receptacle, as shown.

EDWARD F. KAUTZ.
